BOBBIN

Clarence E. Cundey, Philadelphia, Pa.

Application February 11, 1935, Serial No. 6,004

1 Claim. (Cl. 242—120)

My invention relates to an improvement in bobbins of the general character described in United States Patent No. 1,834,914 of December 1, 1931, and it relates more particularly to the provision of means in the butt of the bobbin where it engages the spindle to effect firmer engagement between the bobbin and the spindle, in order to insure positive turning of the bobbin with the spindle, particularly on the starting and stopping thereof, and further to prevent the bobbin from rising with respect to the spindle due to centrifugal force resulting from the rapid rotation of the bobbin and the spindle.

My invention still further relates to simple, novel means for effecting this purpose without adding to the cost of manufacture or assembly.

In the accompanying drawing:

Fig. 1 represents a fragmentary vertical section of a bobbin and spindle.

Fig. 2 represents a section on line 2—2 of Fig. 1.

Fig. 3 represents a section on line 3—3 of Fig. 1.

Fig. 4 represents a perspective view of a bushing embodying my invention.

Fig. 5 represents a vertical sectional view of the bushing shown in Fig. 4.

Referring to the drawing in which like reference characters indicate like parts, 1 designates the blade of the spindle to which is rigidly secured the whirl 2. The extension 3 of the whirl 30 2 is provided with a recess 4 which is covered by a cap 5, the upper face of which forms a seat of the bobbin 6. The spindle is provided with a plurality of symmetrical, evenly spaced clutch members 8 which fulcrum at 9 against the blade 35 1 and which are provided with the bottom feet 10 which are tensioned by the spring 12. The upper ends of the clutch members 8 are retained by the pendent sleeve 14. The structure so far described is conventional and forms no part of 40 the present invention.

The bobbin 6 is provided with the bottom enlarged portion 16 which is adapted to seat on top of the cap 5 and which is adapted to engage the clutch members 8. Usually in order to minimize wear the enlarged bottom portion 16 of the bobbin 6 is provided with a metal bushing which frictionally engages the clutch members 8. In order to accomplish the object of my invention, namely: to insure proper friction between the 45 bobbin and the spindle and to guard against the tendency of the bobbin to rise from the spindle due to centrifugal force resulting from fast rotation of the spindle, I utilize a particular form of bushing of the general character illustrated 50 in Figs. 4 and 5, which bushing is provided with

the substantially cylindrical body portion 18, the bottom outwardly flared flange 19, and the upper portion which is formed in the inwardly extending projections 21 and outwardly extending pockets or recesses 20. The bottom flange 19 is 5 adapted to engage a corresponding seat in the bottom of the bobbin 6, as will be seen in Fig. 1, and the cylindrical portion 18 is adapted to engage a corresponding cylindrical portion of the internal opening in the lower part of the bobbin, 10 also shown in Fig. 1. The enlarged pockets 20 and the intermediate inward projections 21 are adapted to engage corresponding pockets and recesses 22 and 23 which are preformed in the upper part of the internal opening in the lower portion 15 of the bobbin. After the bobbin has been assembled in position, as shown in Fig. 1, a plurality of punched pricks 24 are formed in the cylindrical body 18 and are made to penetrate into the body of the bobbin, thus securing the bobbin 20 fast to the bushing to insure rotation of the bobbin and the bushing together. The enlarged pockets 20 are adapted to accommodate the upper outwardly flaring portion of the clutch members 8, and when the spindle is rotated at high 25 speed centrifugal force not only tends to raise the bobbin from the spindle but also throws the upper portions of the clutch members 8 outward radially so that the upper portions of the clutch members 8 are thrown out radially against the 30 pockets 20. In this construction the inwardly offset upper edge 25 of the cylindrical portion 18 now forms a stop ring which will engage the lower portions of the clutch members, the upper portions of which have been thrown out radially 35 by the centrifugal force resulting from rapid rotation, and will thus prevent the rise of the bobbin from the spindle. The formation of alternate pockets 20 and inward projections 21 in the bushing and the registration of the clutch members 8 with the pockets 20 serve to key the bushing to the clutch on the spindle, thereby 40 insuring positive engagement therebetween and assuring the turning of the bobbin with the rotation of the spindle.

By this construction I have found that I have achieved the right amount of frictional engagement both vertically and radially to effect unitary turning of the bobbin and the spindle and to prevent the rising of the bobbin from the spindle as 50 contradistinguished from other means heretofore employed which, while effecting sufficient engagement between the bobbin and the spindle, nevertheless rendered the manual disengagement of the bobbin from the spindle, when it was 55

necessary to do so, extremely difficult, due to the fact that the bobbin is normally covered completely with yarn when it is ready to be removed, all except the upper tip thereof, thereby affording 5 very little gripping or holding area, which makes it difficult to disengage a bobbin too tightly engaging the spindle, it being understood that it is not permissible to grasp the bobbin over the part thereof which is covered by yarn, since handling 10 may seriously damage the yarn. Another advantage of my construction over previous constructions resides in the firmer engagement of the bushing with the bobbin, due to spinning of the bushing within the bobbin to conform to the 15 particular contour thereof as contradistinguished between a driven fit of a straight bushing into a bobbin which sooner or later tends to loosen and requires replacement. It is to be understood

that, if desired, I may extend the bottom end of the bushing outwardly and upwardly completely to cover or encase the bottom lower portion of the bobbin.

I claim:

A bobbin having the lower portion thereof internally bored for engaging the clutch of a spindle, the internal bore in the bottom of said bobbin comprising a lower relatively narrow cylindrical portion and an upper relatively enlarged cylindrical portion, said upper relatively enlarged portion having spaced pockets formed therein corresponding to and adapted to receive the engaging parts of said clutch, and a metallic bushing secured in the bore of said bobbin and conforming to the internal contour of said upper and lower cylindrical portions. 5 10 15
